UNITED STATES PATENT OFFICE.

DAVID SWARTZ AND SAMUEL SWARTZ, OF TOM'S BROOK, VIRGINIA.

IMPROVEMENT IN FASTENINGS OF PLOWS.

Specification forming part of Letters Patent No. **11,575**, dated August 22, 1854.

To all whom it may concern:

Be it known that we, DAVID SWARTZ and SAMUEL SWARTZ, of Tom's Brook, in the county of Shenandoah and State of Virginia, have invented certain new and useful Improvements in Plows; and we do hereby declare that the following is a full, clear, and exact description thereof, reference being had to the accompanying drawings, forming a part of this specification.

The nature of our invention consists in the method of fastening the point and cutter to the plow by constructing them in separate pieces with tongues or flanges which slide horizontally in slots formed in the mold-board and landside, whereby a secure fastening is formed for them without the use of screws or bolts, the passage of the plow through the ground keeping them in their place, thereby rendering their removal easy, making the plow more convenient and efficient in its action, and cheaper and more durable.

Figure I of said drawings represents a perspective view of our plow; Figs. II and III, separate views of our point and cutter, showing two modes of construction of them in single or separate pieces, but we prefer and claim constructing them in separate pieces, as shown in Fig. II, and hereinafter described; Fig. IV, a portion of the landside, showing a projecting bracket, D', which divides the slot *c* in the mold-board and landside into two parts to receive and sustain the flange or tongues of the point and cutter when slid in place.

We cast the mold-board and landside in one piece of metal, extending a slot, *c*, from the foot of the plow to near the upper edge of the landside, and providing a flange or bracket, D, in the bottom edge of the landside, and a flange or bracket, D', projecting inward from the landside, so as to divide the slot *c* into two parts, one of which is to receive a tongue or flange, H, formed on the point, and the other to receive a tongue or flange, F, formed on the cutter.

The cutter and point may be constructed in one single piece, as shown in Fig. III, but this method of construction does not answer so well as that represented in Fig. II.

The point and cutter are formed with tongues or flanges which fit the slot *c*, the upper tongue, or that of the cutter E, fitting and sliding in the upper part of the slot *c* and the lower tongue, H, or that of the point, sliding between the flange D' and flange D, said tongues being provided with shoulders which rest against the edges of the mold-board and landside, so that the sides of the point and cutter when slid in place shall be flush with those of the landside and mold-board.

The point and cutter are formed as represented in Fig. II, so that when slid into place the shoulder G of point presses against the end of the cutter I, which keeps both of them in place without the use of screws or bolts, the action of the plow in the ground answering all the purposes of screws and bolts.

We do not claim constructing the point and cutter in separate pieces, so as to be attached and detached at pleasure; but

We do claim and desire to secure by Letters Patent—

Constructing the mold-board and landside with slots, as described, and the point and cutter with tongues or flanges to fit the said slots, so that the said point and cutter shall slide in horizontally, or nearly so, and form a fastening with the mold-board and landside without the use of screws or bolts, substantially as set forth.

In testimony whereof we have hereunto signed our names before two subscribing witnesses.

SAML. SWARTZ.
DAVID SWARTZ.

Witnesses:

JOHN L. SMITH,
I. BECKWITH WEST.
